(57) **CLAIM**

The ornamental design for a microphone, as shown and described.

DESCRIPTION

FIG. 1 is a front and top perspective view of a microphone, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled portion of the microphone labeled 9 in FIG. 1; and,

FIG. 10 is an enlarged view of an encircled portion of the microphone labeled 10 in FIG. 2.

The evenly-dashed broken lines in the figures illustrate portions of the microphone that form no part of the claimed design. The dash-dot broken lines in FIGS. 1, 2, 9 and 10 encircling portions that are illustrated in enlargements form no part of the claimed design.

1 Claim, 10 Drawing Sheets(56)
